ALFONS H. NEULAND, OF NEW YORK, N. Y.

DYNAMO-ELECTRIC MACHINE.

1,266,302.

Specification of Letters Patent. Patented May 14, 1918.

Application filed February 10, 1915. Serial No. 7,223.

To all whom it may concern:

Be it known that I, ALFONS H. NEULAND, a subject of the Czar of Russia, residing at New York city, in the borough of Manhattan and State of New York, have invented 5 certain new and useful Improvements in Dynamo-Electric Machines, of which the following is a full, clear, and exact description.

My invention relates to dynamo-electric machines and particularly to alternators, and one object of my invention is the production of such a machine, which, with relatively low angular and peripheral speed of 10 its rotative parts, will generate a current having a frequency suitable for wireless signaling.

Another object is the simultaneous generation of such currents of various frequencies with a constant speed of rotation, and the rendering of these currents available for use either selectively or simultaneously, without altering the speed of rotation.

Another object is to provide such a machine in which the rotative parts will be 15 free of all windings.

Another object is the obtaining of a high output by polarizing a unidirectional field and forming strong magnetic poles.

Another object is the provision of suitable means for rigidly supporting the laminated flux conductors in closely spaced relation.

Other general objects of my invention are 20 simplicity and lightness of construction and efficiency in operation.

Still other objects and advantages of my invention will appear from the following description.

In carrying out my invention, I employ a 25 stator having the armature or induced winding disposed circumferentially about it and a field member or source of unidirectional magneto-motive force so arranged that the lines of force act upon the entire circumference of the armature or induced winding.

I also provide two concentric coöperating 30 series of spaced circularly arranged magnetic conductors, the two series being rotative relative to each other, the magnetic conductors of one series being arranged to successively radially aline with those of the other series as they are relatively rotated, and thus provide a revolving magnetic path 35 for the flux, and in effect producing a revolving field. This is preferably effected by

the difference in number of the magnetic conductors in the two series, the number of points of alinement being dependent upon the number of conductors by which the two 40 series differ. It is evident that this rotative magnetic path may be produced by but a single ring in each series or a plurality of rings in each series, the plurality being employed to break the path of the flux more 45 effectively in the non-alined portions, and to enable the increase of the magneto-motive force of the field without increasing the flux density. This enables a larger armature current to flow in the windings and results 50 in a greater output.

The armature or induced winding is arranged so as to be traversed by the revolving magnetic flux, and thereby to have potential induced therein, and it is composed 55 of one or more pairs of pole windings, each pole winding preferably being a complete coil of one or more turns, the successive and adjacent coils or pole windings being oppositely or reversely wound. The field flux 60 consists of two components, that is, the one cutting the clockwise windings and the one cutting the counter-clockwise windings, and, as will later appear, one of the flux components predominates over the other, and 65 the rotation of the magnetic path causes these components to alternately cut each coil or pole winding, and thus generates a potential therein. I, therefore, in the specification and claims, use the term "predominating flux component" to designate that component of the unidirectional field which is the larger component and generates an E. M. F. which determines the direction of 70 the current in the induced winding, and I 75 use the term "opposed flux component" to designate the lesser component of the unidirectional field, which generates an E. M. F. in opposition to that generated by the predominating flux component. The foregoing 80 features are broadly disclosed and claimed 85 in my prior Patent No. 1,211,617, of January 9, 1917.

In my said former application the flux is 90 made to alternate as well as to revolve and 95 the frequency per revolution in the stationary winding is determined by the number of magnetic conductors on the rotating part. In accordance with my present invention in order to increase the frequency per revolution without an increase in the number of 100 magnetic conductors, I employ a plurality 105 of magnetic conductors on the rotating part, and the frequency per revolution is determined by the number of magnetic conductors on the rotating part. In accordance with my present invention in order to increase the frequency per revolution without an increase in the number of 110 magnetic conductors, I employ a plurality

of these reversely wound coils within the space from one point of alinement of the flux conductors to the next successive point of alinement. In order to provide for the generation of a plurality of different frequencies simultaneously, without changing the speed of the rotors, I employ a number of separate windings on the stator, each having a different number of pairs of pole windings between the successive points of full alinement, and I employ switches for selectively connecting any or all of these windings into the external circuit. Since, as above pointed out, the frequency generated in the windings depends upon the numbers of pairs of coils or pole windings between the successive points of alinement of the flux conductors, the variation in the number of pairs of pole windings in the different armature or induced windings will effect the desired difference in frequency.

Also in order to increase the frequency of the generated current, I provide for making the two series of magnetic conductors rotatable in opposite directions, thus increasing the frequency of the alinement of the successive magnetic conductors of the two series.

If a large number of pole windings between alined points is used, the predominating flux may only slightly exceed the opposed flux, resulting in a relatively small potential difference. I employ means for decreasing or reversing the opposed flux, thereby increasing the effective flux. This is done by polarizing the unidirectional field by means of a current of proper phase supplied to the induced or armature winding. In the present instance this polarizing current is supplied by condensers across the terminals of the induced winding or windings.

Further, in accordance with my invention, to mount or support the laminated flux conductors in closely spaced relation, I employ a flange member carrying on one side a ring of non-magnetic material, which is preferably integral therewith, and the ring is provided with spaced radial slots around its entire circumference, into which laminated steel stampings are inserted. The flange member is also provided on its other side with a circumferential slot which intersects all the radial slots in the ring, thereby forming a rectangular opening in the inner end of each slot, into which the inner ends of the laminations are inserted and fit. The outer ends of the laminations are joined together by a ring of preferably non-magnetic material, which holds the laminations rigidly in place, and which is preferably insulated from the ring and from the laminations to eliminate waste currents in the solid metal portions.

My invention also comprehends various

other features of construction and arrangements and combinations of parts, as will hereinafter more fully appear.

I shall now describe the embodiment of my invention illustrated in the accompanying drawings, and shall thereafter point out my invention in claims.

Figure 1 is a transverse vertical section, partially diagrammatic, of a machine embodying my invention, taken on the line 75-1-1 of Fig. 2;

Fig. 2 is a central longitudinal section of the same;

Fig. 3 is an enlarged detail in elevation, of the rings supporting the laminated flux conductors, as viewed from their outer ends, the tongues on the outer ends being omitted for the sake of clearness;

Fig. 4 is a detail of one of the laminated flux conductors, showing sections of the end retaining ring and of the insulation slightly separated;

Fig. 5 is a plan of a laminated flux conductor;

Figs. 6, 7 and 8 are diagrams of the three armature windings and their respective circuits, Fig. 6 showing the armature winding composed of one pair of pole windings, Fig. 7 that composed of two pairs of pole windings, and Fig. 8 that composed of three pairs of pole windings.

Figs. 6^a, 6^b, and 6^c, are diagrams representing the flux cutting the armature winding shown in Fig. 6 under the conditions when there is no condenser current, when the magneto-motive force of the condenser current just equals that of the opposed flux, and when it exceeds the opposed flux, respectively.

Figs. 7^a, 7^b and 7^c are similar diagrams representing the flux cutting the armature winding shown in Fig. 7 under the same conditions, respectively.

Figs. 8^a, 8^b and 8^c are similar diagrams representing the flux cutting the armature winding shown in Fig. 8, under the same conditions, respectively.

In the illustrated embodiment of my invention the magnetic flux traverses the stator and two oppositely rotatable members, the field and armature or induced windings being carried by the stator, thus leaving the rotatable members free of all windings. The stator comprises an annular laminated soft iron stator element or core, 1, provided at its inner periphery with a circumferential series of longitudinal induced-winding-receiving slots or openings 2, preferably not intersecting the inner periphery, as shown. The induced windings are arranged in these slots, as will be hereinafter described.

The laminated stator element 1 is arranged within and carried by an annular portion of the housing of the machine, which is shown as integral with one of the side plates 3, the

housing being completed by a complementary side plate 4. The housing is stationary, being carried by the base 5 of the machine, and the side plates are provided with hub portions 3' and 4', respectively, which serve as bearings for the rotative parts. The source of magnetic flux is shown as a field coil 6 fitted over and carried by an annular rib or flange 7 on the inner face of the side 10 plate 3.

Each rotatable member comprises a series of circumferentially arranged equally spaced laminated flux conductors, the two series being arranged concentrically within the 15 stator element 1, and preferably each series is composed of a plurality of spaced circular sets or rings, here shown as two, the rings of the two members being arranged in alternate relation when assembled, as shown. 20 As above explained, the construction for supporting and spacing the laminated conductors is such as to permit of their close spacing, while at the same time furnishing a rigid support therefor. My invention with 25 respect to this construction, however, is not claimed broadly herein, but is claimed in my Patent No. 1,237,944, of August 21, 1917. The two opposing flange members 8 and 9 of non-magnetic material, are disposed in 30 parallel planes at right angles to the axis of the machine, and are mounted for rotation in opposite directions. The flange member 8 has on its inner face the two spaced concentric rings or annuli 10 and 11 integral therewith. And the flange member 9 also has on its inner face the two similarly 35 spaced integral concentric annuli 12 and 13. The four annuli are of such diameter and are so spaced that they fit together in close 40 relation and alternate from the exterior to the interior, the annulus 10 being the outermost and closely associated with the stator core 1, and the annulus 13 being the innermost, and the annulus 12 being disposed 45 within the annular space between the annuli 10 and 11, and the annulus 11 being disposed within the annular space between the annuli 12 and 13.

Each flange member is provided on its 50 outer face with two circumferential grooves 14, respectively, opposite the two annuli, and each annulus is provided with equally and closely spaced radial slots 15, which extend part way into the flange member and 55 intersect the respective grooves 14, thereby forming rectangular holes 16. The laminated flux conductors 17 fit into the slots 15 and are of such width as to be flush with the faces of the annuli. A tongue is formed 60 on each end of the flux conductors 17, that on one end extending through the opening 16 into the groove 14. The outer ends of the annuli are reduced in thickness to form a circumferential tongue conforming to that 65 on the outer ends of the flux conductors 17,

and a grooved end ring 18 fits on this tongue and that of the outer ends of the flux conductors and thus locks the flux conductors securely in their respective slots. To eliminate waste currents, an annular insulation 70 19 is interposed between the retaining ring 18 and the annulus.

For convenience of reference the series of flux conductors on the member 8 may be referred to as the outer series, and that on the member 9 as the inner series. There are fifty-nine equally spaced conductors 17 in the outer series, this number of course being duplicated in each circular set of the series and those of the two sets being in radial 80 alinement; and there are sixty equally spaced conductors 17 in the inner series. It is therefore apparent that the conductors of the two series will be alined at one point of the circumference and will be progressively 85 more and more off-set between the point of complete alinement and a point opposite the point of alinement, at which latter point they will be completely staggered or off-set. Manifestly the number of points at which 90 the flux conductors on the two members aline is determined by the number of conductors by which the two series differ, and if, for instance, those on one member exceed those on the other member by two, there will 95 be two points of full alinement with two points of complete off-set.

It is obvious that the rotation of one of the two rotative members for a distance equal to the pitch of the flux conductors of that member, will cause the conductors of the two series to progressively aline from point of full alinement to point of full alinement, which in the illustrated construction is 360° , thus causing the circumferential progression of the magnetic path formed by the alined conductors for a complete revolution. In other words, the relative angular velocity between the magnetic path and the two rotatable members is 59 to 1 105 and 60 to 1, respectively, that is, each revolution of the outer series of conductors 110 causes the closed magnetic path to make fifty-nine revolutions and each revolution of the inner series of conductors causes the 115 closed magnetic path to make sixty revolutions, while the simultaneous revolution of both series in opposite direction causes the path to make a number of revolutions equal to the sum of the conductors in the two 120 series, or one hundred and nineteen.

The outer series of flux conductors is carried by a soft iron rotative core member 20, which is a solid casting and which forms part of the magnetic path, the flange member 8 being mounted upon the periphery of the core member 20 outside of the radial plane of the stator element 1, and the core member 20 also carries on its periphery an annular laminated soft iron complementary 125 130

core element 21 in the radial plane of the stator element 1 and of the coöperating series of flux conductors 17. This complementary core element 21 is provided on its outer periphery with a series of fifty-nine equally spaced teeth 22, which are in radial alinement with the fifty-nine flux conductors of the outer series in the annuli 10 and 11, and which coöperate therewith in forming a closed magnetic path.

The two rotors are driven by the motors 23 and 24, respectively, in the directions indicated by the arrows. The rotor of the motor 24 is fixed on the outer end of the central shaft 25, which bears at the end adjacent the motor 24 in the hub 4' and at the other end in the transmission for the other rotor, anti-friction bearings being provided, as indicated. The hub portion of the flange member 9 is also keyed to the shaft 25 just inside of the side plate 4, and through this connection rotation is transmitted to the inner series of magnetic conductors. The hub of the core member 20 of the other rotor 25 is keyed to a sleeve 26 surrounding the shaft 25 and bearing at its inner end in the hub portion of the flange member 9, and at its outer end in the hub 3', anti-friction bearings being provided, as indicated. The rotor of the motor 23 is fixed to a stub shaft 27 arranged in line with the shaft 25, and the stub shaft 27 is coupled to the sleeve 26 by a coupling member 28, to which the stub shaft and sleeve are both keyed, and which 35 forms a bearing for that end of the shaft 25, as shown. Through this connection rotation is transmitted from the motor 23 to the outer series of flux conductors.

It is now clear that the rotation of the two rotatable elements in opposite directions produces a rotating unidirectional magnetic field which has many times the velocity of the elements, and this rotating magnetic field cuts the windings on the stator element 1 and induces a high frequency potential therein. In my said former application, in which a revolving field is produced by the rotation of one element, the circumferential distance from one point of full alinement, 45 consisting of one alined portion and one unalined portion, constitutes a pole pair, and the two portions respectively oppose two properly spanned pole windings, and in this 50 construction the frequency per revolution of the generated current is determined by the number of teeth on the rotated element. In accordance with my present invention, I increase the frequency per revolution of the 55 generated current by providing more than one pair of pole windings within this space. I also provide for the simultaneous generation of a plurality of different frequencies without changing the speed of rotation, by 60 employing a plurality of independent arma-

ture windings, each having a different number of pairs of pole windings within the space from one point of full alinement to the next successive point of full alinement. This is of particular advantage in wireless 70 signaling where it is often desirable to change quickly from one frequency to another, and with embodiments of my invention this can be done by merely connecting one or another of the armature windings into 75 the consuming circuit by means of switches.

In the illustrated construction I have shown three independent armatures or induced windings, 29, 30, and 31, circumferentially arranged on the stationary core 1 in 80 the holes or slots 2. The windings are arranged in a series of coils, the successive coils being oppositely wound and two successive coils forming a pair of pole windings. The lowest frequency is generated in that 85 winding which is composed of as many pairs of pole windings as the number of flux conductors by which the two series differ, or in the illustrated construction, in a winding composed of one pair of pole windings. As 90 the number of pairs of pole windings is increased the frequency is correspondingly increased, the frequency per revolution being determined by adding the number of flux conductors in one series to that of the second series, and multiplying the sum by the 95 number of pairs of pole windings within the space from one point of full alinement to the next successive point of full alinement. Since in the illustrated machine there is but 100 one point of full alinement, this distance is 360°, and I have therefore shown the winding 29 as composed of one pair of pole windings, and the winding 30 as composed of two 105 pairs of pole windings and the winding 31 as composed of three pairs of pole windings. These coils are shown diagrammatically in Figs. 6, 7 and 8, respectively. These are merely examples of possible windings, although the number of pairs of pole windings 110 within the space between the successive points of alinement may be increased to a certain limit, which will be later explained. The flux conductors 17 are preferably thin, as is shown in the drawing, in order that the 115 fully or partly alined conductors will substantially oppose only one pole winding when the span or pitch of the windings is small on account of there being relatively a large number of them.

Since the flux at all points of the circumference is unidirectional, the flux through the pole windings may be divided into two components, one traversing all clockwise pole windings and one traversing all counter-clockwise pole windings. When the center of the alined portion opposes the center of a clockwise pole winding, the flux component traversing all clockwise pole windings will 125 be larger than the flux component traversing 130

all counter-clockwise pole windings, and the latter flux component generates a potential smaller than and in opposition to that generated by the first component. The first component will hereinafter be referred to as the predominating flux component, and the latter as the opposed flux component.

It will now be seen that as the number of pairs of pole windings between two successive points of alinement is increased, the predominance of the predominating flux over the opposed flux becomes less, other conditions remaining constant, and, as previously indicated, there is, therefore, a limit beyond which the pole windings cannot practically be increased. When the number of pairs of pole windings between two points of alinement is large, the predominating flux may be only slightly larger than the opposed flux, resulting in rather weak field poles and only a small active flux and terminal potential difference. In accordance with my invention I provide for armature excitation which serves to form powerful magnetic field poles.

This means consists, in the embodiment shown, of means for supplying a magnetizing current to the armature windings which is substantially in line or in phase with the point of full alinement of the flux conductors and with the flux, and with all other points opposed by similarly wound pole windings. Specifically, this source of magnetizing current is one or more condensers connected across the terminals of each armature winding, as indicated in Figs. 6, 7 and 8. The magneto-motive force due to the armature magnetizing current is, at the said points, in the same direction as that due to the field current, and hence it materially strengthens all the poles traversed by the predominating flux component. Since, in the form shown, all the pole windings are connected in series, the magnetizing current is of equal magnitude in that half of the pole windings which is traversed by the opposed flux component. Hence, the armature magnetizing current in the latter pole windings opposes the magneto-motive force of the field, and if the two are equal the opposed flux through these pole windings is eliminated. When the armature magnetizing magneto-motive force exceeds the field magneto-motive force, the flux through the pole windings traversed by the opposing flux is reversed, and is no longer an opposed flux, but is now active and must be added to the predominating flux since it generates in the windings a potential which is in the same direction as that due to the predominating flux.

This phenomenon is illustrated in the diagrams of Figs. 6^a to 8^c. These diagrams are developments of the fluxes and the windings, and represent the conditions which obtain during one revolution of the magnetic field.

Figs. 6^a, 6^b and 6^c represent the flux cutting the winding 29 of Fig. 6, first, when there is no armature magneto-motive force by reason of condenser excitation, second, when the armature magneto-motive force by reason of the condenser excitation just equals the field magneto-motive force, and third, when the armature magneto-motive force by reason of the condenser excitation exceeds the field magneto-motive force. The active flux, that is, the difference between the predominating and opposed flux, is represented by the shaded area. Since the induced winding 29 has but one pair of pole windings, each pole winding spans 180 mechanical degrees, and hence there is but one cycle during a revolution of the field, and the distance between the lines A and B, which is 180 electrical degrees is also 180 mechanical degrees. The predominating flux component is cutting the pole winding which spans the space between the lines A and B, and the opposed flux component is cutting the other pole winding which spans the space from line B to line A. The quantity of opposed flux is represented by the areas b, b, and therefore the areas a, a, which are equivalent to the areas b, b, are deducted from the predominating flux area, leaving the active flux represented by the shaded portion.

In the condition represented by Fig. 6^b, the armature magneto-motive force by reason of the condenser excitation just neutralizes the opposed flux while at the same time increasing the predominating flux, and therefore, not only is the area representing the predominating flux larger than in Fig. 6^a, but it is all shaded to represent active flux, since the areas b, b are eliminated and hence the equivalent areas a, a.

In the condition represented by Fig. 6^c, not only is the predominating flux still further increased by the greater armature magneto-motive force, but the opposed flux has now been reversed and has become active, as represented by the areas b', b', the entire active flux being represented by the sum of the shaded portions both above and below the line.

Figs. 7^a, 7^b and 7^c represent the flux traversing the induced winding 30 of Fig. 7 under the three same respective conditions. Here, since the span of each pole winding is but 90°, there are two cycles for each revolution of the magnetic field, and hence the distance between the lines A and B, which represents the span of the several pole windings, is 180 electrical degrees. Reading toward the right, the two pole windings spanning the spaces between the lines A and B, are traversed by predominating flux components, while those spanning the two spaces between the lines B and A are traversed by opposed flux components. Hence the areas

a, a, d, d, represent predominating flux, and the areas b, b, c, c, represent opposed flux. The areas c, c substantially neutralize the areas d, d and the areas b, b substantially neutralize the areas a, a, thereby leaving the shaded area as the active flux.

In Fig. 7^b, as in Fig. 6^b, the opposed flux is eliminated and the predominating flux components are increased by the armature 10 magneto-motive force, and hence the areas d, d have now become active poles. In Fig. 7^c, as in Fig. 6^c, the predominating flux components are still further increased, and the opposed flux components are now reversed and have become active, the entire active flux being represented by the shaded portions both above and below the line.

Figs. 8^a, 8^b and 8^c represent the flux traversing the induced winding 31 of Fig. 8. 20 Here there are three cycles to each revolution of the magnetic field, since the span of each pole winding is but 60°, and therefore in the diagram the distance between the lines A and B, which is the distance spanned by 25 each pole winding, is 180 electrical degrees, but only 60 mechanical degrees. Here again, reading toward the right, the three pole windings spanning the spaces between the lines A and B are traversed by predominating flux components, while those spanning the three spaces between the lines B and A are traversed by opposed flux components. Hence the areas a, a, d, d, e, e, represent predominating flux, and the areas b, 30 b, c, c, f, f, represent opposed flux. The areas f, f substantially neutralize the areas e, e, the areas c, c substantially neutralize the areas d, d, and the areas b, b substantially neutralize the areas a, a, thereby leaving the shaded area as the active flux.

In Fig. 8^b, as in Figs. 6^b and 7^b, the opposed flux is eliminated, and the predominating flux components are increased, and hence the areas d, d, e, e have now become 45 active poles. In Fig. 8^c, as in Figs. 6^c and 7^c, the predominating flux components are still further increased, and the opposing flux components are reversed and have become active, as indicated.

50 Thus it will be seen that, while the field current establishes the two flux components, fixes the frequency in the several windings and induces a potential therein, serving to energize the condenser, the condenser current polarizes the field and creates powerful magnetic poles which enable the generation of large quantities of current.

As is shown in Figs. 6, 7 and 8, switches 33 are provided which control the connection 55 of the condensers into the armature or induced circuits, and also the connection of the armature or induced windings into the external circuit 34.

It is manifest that with embodiments of 60 my invention large quantities of high fre-

quency currents, either single-phase or polyphase, suitable for purposes of wireless signaling, may be produced with but low angular and peripheral velocity of the rotating parts, and that the frequency of the current may readily be changed without changing the speed of the rotating parts.

It is obvious that various modifications may be made in the construction shown in the drawings and above particularly described, within the principle and scope of my invention.

I claim:

1. A dynamo-electric machine comprising a source of magnetic flux, a stator, two concentric rotors mounted co-axially with the stator and rotatable in opposite directions, the three members being traversed by the magnetic flux and each rotor comprising a series of spaced magnetic conductors and the conductors of one series differing in number from those of the other series, whereby the conductors of the two series will radially align at at least one point progressively as the two rotors are oppositely 90 rotated and thereby form a revolving closed magnetic path for the flux having greater angular velocity than the relative angular velocity of the rotors, and an induced winding adapted to be traversed by the magnetic 95 flux and arranged to have a potential generated therein as the magnetic path and flux revolve.

2. A dynamo-electric machine comprising a source of magnetic flux, a stator, two concentric rotors mounted co-axially with the stator and rotatable in opposite directions, the three members being traversed by the magnetic flux and each rotor comprising a series of spaced magnetic conductors and the conductors of one series differing in number from those of the other series, whereby the conductors of the two series will radially align at at least one point progressively as the two rotors are oppositely rotated and thereby form a revolving closed magnetic path for the flux having greater angular velocity than the relative angular velocity of the rotors, and an induced winding circumferentially arranged within the 115 magnetic field and comprising a pair of oppositely wound pole windings arranged in succession within the angular distance from one point of full alinement of the magnetic conductors to the next successive point of 120 full alinement, whereby the revolving magnetic path and flux cause the two pole windings to be alternately cut by predominating and opposed flux components generating a resultant E. M. F. in the induced winding 125 commensurate with the difference between the flux components.

3. A dynamo-electric machine comprising a source of magnetic flux, a stator member, a flux directing member comprising a series 130

of spaced magnetic conductors circumferentially arranged concentric with the stator, a rotor member having a series of spaced magnetic conductors arranged concentric with

- 5 those of the first series and differing in number therefrom, the three members being traversed by the magnetic flux, whereby the conductors of the two series will radially aline at at least one point progressively as
- 10 the rotor is rotated and thereby form a revolving closed magnetic path for the flux having a higher angular velocity than that of the rotor, and a plurality of independent induced windings adapted to be traversed
- 15 by the magnetic flux and so arranged as to be simultaneously acted upon by the revolving flux and to have a different frequency generated thereby in each of said windings.
- 20 4. A dynamo-electric machine comprising a source of magnetic flux, a stator member, a flux directing member comprising a series of spaced magnetic conductors circumferentially arranged concentric with the stator, a rotor member having a series of spaced magnetic conductors arranged concentric with those of the first series and differing in number therefrom, the three members being traversed by the magnetic flux, where-
- 25 by the conductors of the two series will radially aline at at least one point progressively as the rotor is rotated and thereby form a revolving closed magnetic path for the flux having a higher angular velocity
- 30 than that of the rotor, and a plurality of independent induced windings circumferentially arranged within the magnetic field and having respectively different numbers of pairs of oppositely wound pole windings
- 35 arranged in succession within the angular distance from one point of full alinement of the magnetic conductors to the next successive point of full alinement, whereby a different frequency is generated in each induced winding as the closed magnetic path and flux are revolved.

- 3. In a dynamo-electric machine, a magnetic circuit formed partly of a series of laminated flux conductors rotatable in one direction and a second series of flux conductors adjacent to the first series and rotatable in the opposite direction, the flux conductors of one series being so arranged with respect to those of the other that when the flux conductors of one series are alined with the flux conductors of the other series in one portion of the machine they are unalined in another part of the machine, means for producing a magnetic flux through the magnetic circuit, and a plurality of independent induced windings adapted to be traversed by said flux and each comprising a plurality of pole windings, the pole windings of each induced winding differing in pitch from the corresponding pole windings of the other

induced windings, whereby with a uniform speed of rotation potentials of different frequencies are generated in said induced windings.

6. In a dynamo-electric machine, a magnetic circuit formed partly of a series of laminated flux conductors rotatable in one direction and a second series of flux conductors adjacent to the first series and rotatable in the opposite direction, the flux conductors of one series being so arranged with respect to those of the other that when the flux conductors of one series are alined with the flux conductors of the other series in one portion of the machine they are unalined in another part of the machine, means for producing a magnetic flux through the magnetic circuit, and a plurality of independent induced windings adapted to be traversed by said flux and each comprising a plurality of pole windings, the adjacent pole windings of each induced winding being wound in opposite directions and the pole windings of each induced winding differing in pitch from the corresponding pole windings of the other induced windings, whereby with a uniform speed of rotation potentials of different frequencies are generated in said induced windings.

7. A dynamo-electric machine comprising a source of magnetic flux, a stator member, a flux directing member comprising a series of spaced magnetic conductors circumferentially arranged concentric with the stator, a rotor member having a series of spaced magnetic conductors arranged concentric with those of the first series and differing in number therefrom, the three members being traversed by the magnetic flux, whereby the conductors of the two series will radially aline at at least one point progressively as the rotor is rotated and thereby form a revolving closed magnetic path for the flux having a higher angular velocity than that of the rotor, a plurality of independent induced windings circumferentially arranged within the magnetic field and having respectively different numbers of pairs of oppositely wound pole windings arranged in succession within the angular distance from one point of full alinement of the magnetic conductors to the next successive point of full alinement, whereby a different frequency is generated in each induced winding as the closed magnetic path and flux are revolved, and means for independently connecting the several induced windings to an external circuit.

8. A dynamo-electric machine comprising a source of magnetic flux, a stator, two concentric rotors mounted co-axially with the stator and rotatable in opposite directions, the three members being traversed by the magnetic flux and each rotor comprising a series of spaced magnetic conductors and the

- conductors of one series differing in number from those of the other series, whereby the conductors of the two series will radially aline at at least one point progressively as the 5 two rotors are oppositely rotated and thereby form a revolving closed magnetic path for the flux having greater angular velocity than the relative angular velocity of the rotors, and a plurality of independent induced 10 windings circumferentially arranged within the magnetic field and having respectively different numbers of pairs of oppositely wound pole windings arranged in succession within the angular distance from one point 15 of full alinement of the magnetic conductors to the next successive point of full alinement, whereby a different frequency is generated in each induced winding as the closed magnetic path and flux are revolved.
- 20 9. The combination of a dynamo-electric machine comprising a source of magnetic flux, a stator and a rotor traversed by said flux and including means for producing a revolving closed magnetic path for the flux 25 as the rotor rotates, the flux path rotating at a higher angular velocity than that of the rotor, an induced winding circumferentially disposed in the magnetic field and comprising a plurality of pairs of pole windings, the 30 two pole windings of each pair being oppositely wound, the clockwise windings and the counter - clockwise windings being alternately traversed by a predominating and an opposed flux component as the magnetic 35 path and flux rotate, generating thereby a resultant E. M. F. in the induced winding commensurate with the difference between the flux components; and means for supplying a magnetizing current to said winding of 40 such phase as to produce strong magnetic field poles strengthening the predominating flux component and weakening the opposed flux component.
10. The combination of a dynamo-electric 45 machine comprising a source of magnetic flux, a stator and a rotor traversed by said flux and including means for producing a revolving closed magnetic path for the flux as the rotor rotates, the flux path rotating at 50 a higher angular velocity than that of the rotor, an induced winding circumferentially disposed in the magnetic field and comprising a plurality of pairs of pole windings, the two pole windings of each pair being oppositely wound, the clockwise windings and the counter - clockwise windings being alternately traversed by a predominating and an 55 opposed flux component as the magnetic path and flux rotate, generating thereby a resultant E. M. F. in the induced winding; commensurate with the difference between the flux components and a condenser acted upon by said potential and arranged to supply a magnetizing current to said winding of 60 such phase as to establish strong magnetic 65 field poles strengthening the predominating flux component and weakening the opposed flux component.
- field poles strengthening the predominating flux component and weakening the opposed flux component.
11. The combination of a dynamo-electric 70 machine comprising a source of magnetic flux, a stator and a rotor traversed by said flux and including means for producing a revolving magnetic path for the flux as the rotor rotates, a plurality of induced windings circumferentially disposed within the 75 magnetic field and each comprising a different number of pairs of pole windings, the pole windings of each pair being oppositely wound, whereby a different frequency is generated in each induced winding as the rotor 80 rotates; and a condenser connected in circuit with each induced winding and arranged to be acted upon by the potential generated in said winding and to supply a magnetizing current to said winding, thereby establishing strong field poles, and means for independently connecting the several induced windings to an external circuit.
12. The combination of a dynamo-electric 85 machine comprising a source of magnetic 90 flux, a stator, two concentric rotors mounted co-axially with the stator and rotatable in opposite directions, the three members being traversed by the magnetic flux and each rotor comprising a series of spaced magnetic 95 conductors and the conductors of one series differing in number from those of the other series, whereby the conductors of the two series will radially aline at at least one point 100 progressively as the two rotors are oppositely rotated and thereby form a revolving closed magnetic path for the flux having greater angular velocity than the relative angular velocity of the rotors, an induced winding circumferentially arranged within 105 the magnetic field and comprising a pair of oppositely wound pole windings arranged in succession within the angular distance from one point of full alinement of the magnetic 110 conductors to the next successive point of full alinement, whereby the revolving magnetic path and flux cause the two pole windings to be alternately cut by predominating and opposed flux components generating a resulting E. M. F. in the induced winding 115 commensurate with the difference between the flux components; and means for supplying a magnetizing current to said winding of such phase as to produce strong magnetic field poles coöperating with the predominating flux component and acting against the 120 opposed flux component.
13. The combination of a dynamo-electric 125 machine comprising a source of magnetic flux, a stator, two concentric rotors mounted co-axially with the stator and rotatable in opposite directions, the three members being traversed by the magnetic flux and each rotor comprising a series of spaced magnetic conductors and the conductors of 130

- one series differing in number from those of the other series, whereby the conductors of the two series will radially align at at least one point progressively as the two rotors are oppositely rotated and thereby form a revolving closed magnetic path for the flux having greater angular velocity than the relative angular velocity of the rotors, an induced winding circumferentially arranged within the magnetic field and comprising a pair of oppositely wound pole windings arranged in succession within the angular distance from one point of full alinement of the magnetic conductors to the next successive point of full alinement, whereby the revolving magnetic path and flux cause the two pole windings to be alternately cut by predominating and opposed flux components generating a resultant E. M. F. in the induced winding commensurate with the difference between the flux components, and a condenser acted upon by said potential and arranged to supply a magnetizing current to said winding strengthening the predominating flux component and reversing the opposed flux component, thus polarizing the field.
14. The combination of a dynamo-electric machine comprising a source of magnetic flux, a stator member, a flux directing member comprising a series of spaced magnetic conductors circumferentially arranged concentric with the stator, a rotor member having a series of spaced magnetic conductors arranged concentric with those of the first series and differing in number therefrom, the three members being traversed by the magnetic flux, whereby the conductors of the two series will radially align at at least one point progressively as the rotor is rotated and thereby form a revolving closed magnetic path for the flux having a higher angular velocity than that of the rotor, a plurality of independent induced windings circumferentially arranged within the magnetic field and having respectively different numbers of pairs of oppositely wound pole windings arranged in succession within the angular distance from one point of full alinement of the magnetic conductors to the next successive point of full alinement, whereby a different frequency is generated in each induced winding as the closed magnetic path and flux are revolved; a condenser adapted to be connected in circuit with each induced winding and to be acted upon by the potential generated in said winding and to supply a magnetizing current to said winding and establish strong field poles, and means for independently connecting the several induced windings to an external circuit.
15. The combination of a dynamo-electric machine comprising a source of magnetic flux, a stator member, a flux directing member comprising a series of spaced magnetic conductors circumferentially arranged concentric with the stator, a rotor member having a series of spaced magnetic conductors arranged concentric with those of the first series and differing in number therefrom, the three members being traversed by the magnetic flux, whereby the conductors of the two series will radially align at at least one point progressively as the rotor is rotated and thereby form a revolving closed magnetic path for the flux having a higher angular velocity than that of the rotor, a plurality of independent induced windings circumferentially arranged within the magnetic field and having respectively different numbers of pairs of oppositely wound pole windings arranged in succession within the angular distance from one point of full alinement of the magnetic conductors to the next successive point of full alinement, whereby a different frequency is generated in each induced winding as the closed magnetic path and flux are revolved; a condenser adapted to be connected in circuit with each induced winding and to be acted upon by the potential generated in said winding and to supply a magnetizing current to said winding and establish strong field poles, and means for independently connecting the several induced windings to an external circuit.
16. A dynamo-electric machine comprising a source of magnetic flux, a stator, two concentric rotors mounted co-axially with the stator and rotatable in opposite directions, the three members being traversed by the magnetic flux and each rotor comprising a series of spaced magnetic conductors and the conductors of one series differing in number from those of the other series, whereby the conductors of the two series will radially align at at least one point progressively as the two rotors are oppositely rotated and thereby form a revolving closed magnetic path for the flux having greater angular velocity than the relative angular velocity of the rotors, a plurality of independent induced windings circumferentially arranged within the magnetic field and having respectively different numbers of pairs of oppositely wound pole windings arranged in succession within the angular distance from one point of full alinement of the magnetic conductors to the next successive point of full alinement, whereby a different frequency is generated in each induced winding as the closed magnetic path and flux are revolved, and means for independently connecting the several induced windings to an external circuit.
17. A dynamo-electric machine comprising a source of magnetic flux, an annular stator and two annular series of regularly spaced magnetic conductors traversed by said flux, one series of magnetic conductors being rotative and the conductors of the two series differing in number, whereby they will successively radially align as the one

- series is rotated and form a revolving closed magnetic path for the flux, and a plurality of induced windings arranged on the stator circumferentially thereof and each having 5 a different number of pairs of pole windings disposed within the angular space from one point of full alinement of the magnetic conductors to the next successive point of full alinement, whereby a different frequency is 10 generated in each induced winding as the closed magnetic path is revolved.

18. A dynamo-electric machine comprising an annular stator, means carried by the stator for producing a unidirectional magnetic field, two concentric rotors mounted co-axially with the stator and rotatable in opposite directions, the three members being traversed by the magnetic flux and each rotor comprising a series of spaced magnetic 20 conductors and the conductors of one series differing in number from those of the other series, whereby the conductors of the two series will aline at at least one point progressively as the two rotors are oppositely 25 rotated and thereby form a revolving closed magnetic path for the flux having a higher angular velocity than the relative velocity of the two rotors, and an induced winding circumferentially arranged within the magnetic field and comprising a pair of oppositely wound pole windings arranged in succession within the angular distance from one 30 point of full alinement of the magnetic conductors to the next successive point of full 35 alinement, whereby the revolving magnetic path and flux cause the two pole windings to be alternately cut by predominating and opposed flux components generating a resultant E. M. F. in the induced winding 40 commensurate with the difference between the flux components.

19. A dynamo-electric machine comprising an annular stator, means carried by the stator for producing a unidirectional magnetic field, two concentric rotors mounted co-axially with the stator and rotatable in opposite directions, the three members being traversed by the magnetic flux and each rotor comprising a series of spaced magnetic 45 conductors and the conductors of one series differing in number from those of the other series, whereby the conductors of the two series will aline at at least one point progressively as the two rotors are oppositely 50 rotated and thereby form a revolving closed magnetic path for the flux having a higher angular velocity than the relative velocity of the two rotors, and a plurality of independent induced windings circumferentially arranged within the magnetic field and having 55 respectively different numbers of pairs of oppositely wound pole windings arranged in succession within the angular distance from one point of full alinement of the magnetic conductors to the next successive point of full 60 alinement.

of full alinement, whereby a different frequency is generated in each induced winding as the closed magnetic path and flux are revolved.

20. The combination of a dynamo-electric 70 machine comprising an annular stator, means carried by the stator for producing a unidirectional magnetic field, two concentric rotors mounted co-axially with the stator and rotatable in opposite directions, 75 the three members being traversed by the magnetic flux and each rotor comprising a series of spaced magnetic conductors and the conductors of one series differing in number from those of the other series, whereby the conductors of the two series will aline at at least one point progressively as the two rotors are oppositely rotated and thereby form a revolving closed magnetic path for the flux having a higher angular velocity than the 80 relative velocity of the two rotors, a plurality of independent induced windings circumferentially arranged within the magnetic field and having respectively different numbers of pairs of oppositely wound pole 85 windings arranged in succession within the angular distance from one point of full alinement of the magnetic conductors to the next successive point of full alinement, whereby a different frequency is generated 90 in each induced winding as the closed magnetic path and flux are revolved; a condenser adapted to be connected in circuit with each induced winding and to be acted upon by the potential generated in said 95 winding and to supply a magnetizing current to said winding and establish strong field poles, and means for independently connecting the several induced windings to an external circuit. 105

21. In a dynamo-electric machine, a rotor comprising a flange portion provided on one side with a projecting annulus and on the other side with a circumferential groove opposite the annulus, the annulus being provided with slots intersecting the circumferential groove, and a laminated flux conductor fitting into each slot and having a tongue extending into the circumferential groove through the opening formed by the 110 intersection of said groove with the respective slot. 115

22. In a dynamo-electric machine, a rotor comprising a flanged portion provided on one side with a projecting annulus and on the other side with a circumferential groove opposite the annulus, the annulus being provided with slots intersecting the circumferential groove, a laminated flux conductor fitting into each slot and having a tongue 120 extending into its circumferential groove through the opening formed by the intersection of said groove with the respective slot, and removable annular retaining means attached to the opposite end of the annulus 125 130

and engaging the ends of all of the conductors and serving to hold the conductors in their slots.

23. A dynamo-electric machine comprising a source of magnetic flux, a stator member, a flux directing member comprising a series of spaced magnetic conductors circumferentially arranged concentric with the stator, a rotor member having a series of spaced magnetic conductors arranged concentric with those of the first series and differing in number therefrom, the three members being traversed by the magnetic flux, whereby the conductors of the two series will radially aline at at least one point progressively as the rotor is rotated and thereby form a revolving closed magnetic path for the flux having a higher angular velocity than that of the rotor, and an induced winding adapted to be traversed by the magnetic flux and arranged to have a potential generated therein as the magnetic path and flux revolve.

24. A dynamo-electric machine comprising a source of magnetic flux, a stator member, a flux directing member comprising a series of spaced magnetic conductors circumferentially arranged concentric with the stator, a rotor member having a series of spaced magnetic conductors arranged concentric with those of the first series and differing in number therefrom, the three members being traversed by the magnetic flux, whereby the conductors of the two series will radially aline at at least one point progressively as the rotor is rotated and thereby form a revolving closed magnetic path for the flux having a higher angular velocity than that of the rotor, and an induced winding adapted to be traversed by the magnetic flux and arranged to have a potential generated therein as the magnetic path and flux revolve, and means for supplying a magnetizing current in said winding of such phase as to produce strong magnetic field poles strengthening the component of the flux traversing the alined portion of the magnetic path and weakening the component traversing the non-alined portion.

25. A dynamo-electric machine comprising a source of magnetic flux, a stator member, a flux directing member comprising a series of spaced magnetic conductors circumferentially arranged concentric with the stator, a rotor member having a series of spaced magnetic conductors arranged concentric with those of the first series and differing in number therefrom, the three members being traversed by the magnetic flux, whereby the conductors of the two series will radially aline at at least one point progressively as the rotor is rotated and thereby form a revolving closed magnetic path for the flux having a higher angular velocity than that of the rotor, an induced winding adapted to be traversed by the magnetic flux and arranged

to have a potential generated therein as the magnetic path and flux revolve, and a condenser acted upon by said potential and arranged to supply a magnetizing current to said winding of such phase as to establish strong magnetic field poles strengthening the component of the flux traversing the alined portion of the magnetic path and weakening the component traversing the non-alined portion.

26. A dynamo-electric machine comprising a source of magnetic flux, a stator member, a flux directing member comprising a series of spaced magnetic conductors circumferentially arranged concentric with the stator, a rotor member having a series of spaced magnetic conductors arranged concentric with those of the first series and differing in number therefrom, the three members being traversed by the magnetic flux, whereby the conductors of the two series will radially aline at at least one point progressively as the rotor is rotated and thereby form a revolving closed magnetic path for the flux having a higher angular velocity than that of the rotor, and an induced winding circumferentially disposed in the magnetic field and comprising a plurality of pairs of pole windings the two pole windings of each pair being oppositely wound and the two windings being alternately traversed by the flux component of the alined portion of the flux path and the flux component of the non-alined portion of the flux path as the magnetic path and flux rotate, generating thereby a resultant E. M. F. in the induced winding commensurate with the difference between the flux components.

27. A dynamo-electric machine comprising a source of magnetic flux, a stator member, a flux directing member comprising a series of spaced magnetic conductors circumferentially arranged concentric with the stator, a rotor member having a series of spaced magnetic conductors arranged concentric with those of the first series and differing in number therefrom, the three members being traversed by the magnetic flux, whereby the conductors of the two series will radially aline at at least one point progressively as the rotor is rotated and thereby form a revolving closed magnetic path for the flux having a higher angular velocity than that of the rotor, an induced winding circumferentially disposed in the magnetic field and comprising a plurality of pairs of pole windings the two pole windings of each pair being oppositely wound the two windings being alternately traversed by the flux component of the alined portion of the flux path and the flux component of the non-alined portion of the flux path as the magnetic path and flux rotate, generating thereby a resultant E. M. F. in the induced winding commensurate with the difference

between the flux components, and a condenser acted upon by said E. M. F. and arranged to supply a magnetizing current to said winding of such phase as to establish 5 strong magnetic field poles strengthening the former flux component and weakening the latter flux component.

28. A dynamo-electric machine comprising a source of magnetic flux, a stator, two 10 concentric rotors mounted co-axially with the stator and rotatable in opposite directions, the three members being traversed by the magnetic flux and each rotor comprising an annulus provided with longitudinal 15 slots open at one end, a laminated flux conductor disposed in each slot, an annular retaining means on the end of the annulus engaging the conductors and holding them in their slots; the flux conductors of one rotor 20 differing in number from those of the other rotor, whereby the conductors of the two rotors will radially aline at at least one point progressively as the two rotors are oppositely rotated and thereby form a revolving 25 closed magnetic path for the flux having

greater angular velocity than the relative angular velocity of the rotors, and an induced winding adapted to be traversed by the magnetic flux and arranged to have a potential generated therein as the magnetic 30 path and flux revolve.

29. A dynamo-electric machine comprising a flux directing member, a rotor member coöperating therewith to produce a revolving flux path having higher angular velocity 35 than that of the rotor, a source of unidirectional flux radially cutting the two members and distributed by the revolving flux path to produce a revolving unidirectional magnetic field, and an induced winding circumferentially 40 disposed within the magnetic field and comprising a pair of oppositely wound pole windings.

In witness whereof, I subscribe my signature, in the presence of two witnesses.
